W. LOCKETT

BUTTER CUTTER

Filed Dec. 7, 1923

UNITED STATES PATENT OFFICE.

WILLIAM LOCKETT, OF PHILADELPHIA, PENNSYLVANIA.

BUTTER CUTTER.

Application filed December 7, 1923. Serial No. 679,113.

To all whom it may concern:

Be it known that I, WILLIAM LOCKETT, a citizen of the United States, residing in the city and county of Philadelphia, State of Pennsylvania, have invented a new and useful Butter Cutter, of which the following is a specification.

My invention relates to a novel construction of a butter cutter, comprising a suitable frame open at its top and bottom, and having its sides provided with a plurality of tongues or lips of varying sizes which are arranged in horizontal alignment, but in staggered order vertically or out of vertical alignment and adapted to be engaged by a cutting wire whereby the resultant blocks may be cut to any desired size according to requirements.

It further consists of a novel construction of a butter cutter frame having outer horizontal longitudinally-extending upper side flanges, and an actuator for a transverse cutting member having inwardly deflected bottom terminals engaging the under side of said flanges.

It further consists of other novel features of construction and advantage, all as will be hereinafter pointed out.

Figure 1 represents a perspective view of a butter cutter embodying my invention.

Figure 2 represents a vertical section on line 2—2, Figure 1.

Figure 3 represents a transverse section on line 3—3, Figure 2.

Figure 4 represents a perspective view of a print of butter severed by my device.

For the purpose of illustrating my invention, I have shown in the accompanying drawings, a typical embodiment of it by means of which the invention can be advantageously carried out in practice. It is, however, to be understood that the various instrumentalities of which my invention consists can be variously arranged and organized and that the invention is not limited to the exact arrangement and organization of such instrumentalities as herein set forth.

Similar numerals of reference indicate corresponding parts.

50 Referring to the drawings:—

1 designates my novel construction of a butter cutter, the same comprising the sides 2 and the ends 3, which are formed so as to provide the lateral end handle members 4. 55 The upper outer portions of the sides 2 are provided with the longitudinal horizontal

flanges 5, which have the downwardly deflected terminals 6, which act as stop to arrest the movement of the transverse cutter actuator 7, which comprises the handle 8, 60 which is formed into the arms 9, having the inwardly deflected bottom terminals 10, which engage the underside of the horizontal guide flange 5. 11 designates the transverse cutter, which consists of a wire extending between the arms 9, and riding upon the top of the flanges 5. The sides 2 are provided with a series of upper lips or tongues 12 arranged in horizontal alignment and below said tongues is arranged another row 70 of tongues 13 of lesser width, but out of vertical alignment with said tongues 12. Below the tongues 13 is arranged in horizontal alignment another row of tongues 14, which are staggered with respect to the 75 tongues 13. The lower row of tongues 15 are in horizontal alignment and are staggered with respect to the tongues above. The tongues are of varying dimensions, so that cuts of different widths may be formed. 80 The cutting wire 16 is shown as hooked on the tongues 14, and positioned to form the transverse cutting wires 17, whose terminals may be tied or fastened in any desired manner, as may be the terminals of the longitudinal wire 18. In Figure 4 I have shown 85 a print of butter 19 as severed by my device, the line 20 showing the cut made by the wire 18, the line 21 showing the cut made by the wire 11 and the lines 22 showing the cut 90 made by the wires 17. In using the device, it is pressed down upon a print of butter, as will be understood from Figure 3, by pressing on the handles 4, whereupon the print of butter after the cutter is removed 95 will appear as seen in Figure 4. The transverse cutter 11 can be readily actuated by grasping the handle 7, and the lower terminals are readily guided by their contact with the horizontal flanges 5. By the employment of the lips 12, 13, 14 and 15 of varying sizes in conjunction with the cutting wires 17 the butter can be readily cut into sections of varying widths, as is evident.

100 The transverse cutter 11 may be pulled or pushed through the severed sections of the butter to cut it in half horizontally on the line 21, the frame 7 being adapted by its lips 10 and the flanges 5 on the frame to be 110 fulcrumed on the latter and so may be turned to the right and left thereon to pull

or push the wire 11 through the butter on said line 21, as desired or most convenient.

Having thus described my invention, what I claim as new and desire to secure by Letters Patent, is:—

- 10 1. A butter cutter comprising a frame, open at its top and bottom and provided with sides having a plurality of outwardly deflected lips of varying sizes arranged in rows in horizontal alignment but in staggered order vertically and out of vertical alignment, transverse handles extending across each end of said frame, removable parallel cutters engaged with a desired series of said lips and extending transversely across the lower bottom edge of said frame, longitudinally extending horizontal guide flanges on the outer upper portions of said frame terminating in deflected terminals, a handle having arms provided with inwardly deflect- 30 ed terminals engaging the underside of said longitudinal flanges and a transverse cutting wire having its ends secured to said handle arms and slidable upon the top of said longitudinal edge flanges.
- 15 2. A butter cutter, comprising a frame, open at top and bottom and provided with sides having a plurality of outwardly deflected lips of varying sizes arranged in rows in horizontal alignment but in staggered order vertically and out of vertical alignment, transverse handles extending across each end of said frame, removable parallel cutters across the lower bottom edge of said frame.
- 20

3. A butter cutter, comprising a frame, 25 open at top and bottom and provided with sides having a plurality of outwardly deflected lips of varying sizes arranged in rows in horizontal alignment but in staggered order vertically and out of vertical align- 30 ment, transverse handles extending across each end of said frame, removable parallel cutters engaged with a desired series of said lips and extending transversely across the lower bottom edge of said frame, longitudi- 35 nally extending horizontal guide flanges on the outer upper portions of said frame terminating in deflected terminals, a handle having arms provided with inwardly deflect- 40 ed terminals engaging the underside of said longitudinal flanges and a transverse cutting wire having its ends secured to said handle arms and slidable upon the top of said longitudinal edge flanges.

WILLIAM LOCKETT.
